CLAIM

We claim the ornamental design for a flush glazing mold for a modular building system, as shown and described.

DESCRIPTION

FIG. 1 is a perspective view of a first embodiment flush glazing mold for a modular building system constructed in accordance with our new design;

FIG. 2 is an end elevation view thereof;

FIG. 3 is a side elevation view thereof;

FIG. 4 is a top plan view thereof;

FIG. 5 is a bottom plan view thereof;

FIG. 6 is a perspective view of a second embodiment flush glazing mold for a modular building system constructed in accordance with our new design;

FIG. 7 is an end elevational view thereof;

FIG. 8 is a side elevation view thereof;

FIG. 9 is a top plan view thereof; and,

FIG. 10 is a bottom plan view thereof.

The flush glazing mold for a modular building system has been broken in the center indicating indeterminate length.
